Primary Examiner — Cynthia Ramirez(74) *Attorney, Agent, or Firm* — Nicole Davidson; Waller Lansden Dortch & Davis(57) **CLAIM**

The ornamental design for a valve cover, as shown and described.

DESCRIPTION

FIG. 1 is a perspective top view of the valve cover of the present invention;

FIG. 2 is another perspective top view of the valve cover of FIG. 1;

FIG. 3 is a perspective bottom view of the valve cover of FIG. 1;

FIG. 4 is a top view of the valve cover of FIG. 1;

FIG. 5 is a side elevation view of the valve cover of FIG. 1;

FIG. 6 is a bottom view of the valve cover of FIG. 1;

FIG. 7 is a back elevation view of the valve cover of FIG. 1; and,

FIG. 8 is a front elevation view of the valve cover of FIG. 1. The portions drawn in broken lines are for illustrative purposes only and form no part of the claimed design.
